UNITED STATES PATENT OFFICE

CHARLES F. RUBEL AND FREDERICK F. ZEIER, OF CHICAGO, ILLINOIS, ASSIGNEES TO UNION SPECIAL MACHINE COMPANY, OF CHICAGO, ILLINOIS, A CORPORATION OF ILLINOIS

THREAD CONTROLLING MECHANISM FOR SEWING MACHINES

Application filed December 26, 1929. Serial No. 416,611.

The invention relates to new and useful improvements in a thread controlling mechanism for sewing machines, and more particularly to a thread controlling mechanism for the thread carrying looper of a sewing machine.

In an application filed by Norman V. Christensen, Charles F. Rubel and Frederick F. Zeier, August 2, 1928, Serial No. 297,059, 10 a rotating thread controlling member is shown, described and claimed, wherein the threads pass across the controller in parallel planes at right angles to the axis of rotation of the thread controlling member, and where- 15 in said member is provided with means for taking up and casting off the threads during the rotation of the thread controlling element. In a controller of this type it is very important that the thread guides be disposed 20 in a predetermined set position relative to said controlling element.

An object of the invention is to provide a thread controller of the above type wherein the thread guides are rigidly attached to a 25 supporting means, which supporting means in turn is mounted so that the thread guides may be simultaneously moved to a position where they are accessible for threading and then returned to a fixed predetermined position relative to the thread controlling member.

In the drawings:

Figure 1 is a plan view of the parts beneath the work support showing the looper 35 operating mechanism and the improved thread controller.

Fig. 2 is a view partly in front elevation and partly in section of the parts shown in Fig. 1.

Fig. 3 is a sectional view on the line 3—3 of Fig. 1, the thread controller being broken away to show the support for the thread guides.

Fig. 4 is a perspective view of the thread guides and the supporting means therefor, one of the guides being separated from its support to show more clearly the structure thereof.

The invention is directed to the means for 50 supporting the thread guides used in connec-

tion with a rotating thread controlling element so as to direct the threads in separate planes at right angles to the axis of rotation of said controlling element into contact with the peripheral surface of the controlling element. These thread guides are mounted so that they may be simultaneously turned to a position which renders them accessible for threading. Said thread guides are rigidly attached to a supporting shaft mounted in 55 a suitable bracket and said shaft may be manually turned so as to raise the thread guides to a position where they are accessible for threading. A spring is provided which holds said shaft with the thread guides in raised 60 position. When the thread guides are lowered to operative position relative to the thread controlling member there is a stop means which limits their movement and a spring for yieldingly holding the support for 65 the thread guides against the stop means and thus holding said thread guides in proper 70 cooperative position relative to the thread controlling member.

Referring more in detail to the drawings, 75 the invention is shown as applied to a sewing machine which includes a supporting bed 1 on which the main operating shaft 2 is mounted for rotation. As shown in the drawings, there are two loopers 3 and 4. These loopers 80 are mounted on a carrier 5 which is oscillated by means of a link 6 connected to an arm carried by a rock lever 7 which in turn is oscillated by an eccentric 8 carried by the main shaft 2. The looper carrier 5 is mounted on a looper rocker 9 which in turn is oscillated for giving needle avoiding movements to the loopers by means of an arm 10 to which an eccentric strap 11 is connected.

Mounted on the main shaft 2 is the thread 85 controlling member 12. Said thread controlling member includes a central cam shaped member and two circular discs 13 and 14, one on each side of the cam member. This cam member is provided with a radially projecting portion which engages the threads for taking up the same. This radially projecting portion is slotted so that the threads when moved laterally will be cast from the projecting portion into the slots and thus 90 95 100

slack given quickly to the threads. The means for casting the thread off from the shoulder is mounted on and movable with the thread controlling element. This type of rotating thread controlling element which takes up and casts off the threads forms no part of the present invention per se, but is shown, described and claimed in the application above referred to.

10 Associated with this thread controlling element are thread guides for the threads. The threads pass from the supply through a fixed thread guide 16 which is provided with a series of thread eyes 16a having threading 15 slots 16b leading thereto. The thread controlling element, as illustrated in the drawings, is shown as used in connection with a thread carrying looper mechanism, and inasmuch as there are two loopers there will be 20 two threads led from the supply through this thread guiding means 16. These two threads are indicated at *l* and *l'* in the drawings.

The threads after passing the thread guiding means 16 pass through thread eyes 17 and 25 18 respectively formed in an arm 19. They then cross the thread controlling element in planes spaced from each other and at right angles to the axis of rotation of the thread 30 controlling element. The threads pass through thread guides 20 and 21 respectively in the arm 22 at the other side of the thread controlling element and from this point the threads are led to the loopers.

35 Mounted on the bed plate 1 of the machine is a supporting bracket 27. Said bracket has two bearings 28, 28 and mounted in said bearings is a shaft 29. A block 30 is secured to the shaft and disposed between the bearings 40 28, 28 and this holds the shaft from endwise movement. Mounted on the end of the shaft which projects from the bearings is a supporting block 31. The arm 19 is bolted to this block 31 by screws 32, 32 passing through 45 slots 33, 33 in the bracket base 34 with which the arm 19 is integrally formed. These slots are elongated so that the arm may be raised and lowered on the support.

The arm 22 is provided with an integral 50 bracket base portion 35. This bracket portion is secured to the block 30 by means of a screw 36 and a post 37 which functions as a screw. The post and screw pass through elongated slots in the base so that the arm 22 55 may be raised and lowered on its supporting block.

The block 30 is provided with an inclined 60 face 38 and also an inclined face 39, which faces intersect to form a shoulder 40. A leaf 65 spring 41 secured to the bracket 27 bears against this shoulder 40. When the arm 22 is moved to the position shown in full lines in Figs. 2 and 4 the spring bearing against the shoulder will force said arm in a downward 70 direction until it strikes the bracket 27 which

operates as a stop means for limiting the further downward movement of the arm. When the arm is raised to the broken line position shown in Fig. 2, the spring then bearing against the inclined face 39 will hold the 70 arm in raised position.

The post 37 serves as a handle for oscillating the shaft 29 to raise the arms 19 and 22 to the dotted line position in Fig. 2, and also serves as a handle for manually lowering these 75 arms to position where they cooperate with the thread controlling element. The arms are simultaneously raised and simultaneously lowered. The arms are both rigidly attached to the same shaft 29, and therefore, in both 80 their raised and lowered positions will remain in a fixed position relative to each other. If there is any shifting of the set position of one, the other also will be shifted to the same extent. This insures that the threads 85 when the thread guides are in normal position for cooperation with the thread controlling element will be passed in parallel planes with exactness across the thread controlling element. When the thread guides are 90 raised, the thread guides are then positioned so that they may be readily threaded and after they are threaded then they are simultaneously lowered, as noted, and the threads brought into engagement with the thread controlling element.

It is obvious that minor changes in the details of construction and the arrangement of the parts may be made without departing from the spirit of the invention as set forth 100 in the appended claims.

Having fully described our invention, what we claim as new and desire to secure by Letters Patent, is:—

1. A thread controlling mechanism for 105 sewing machines including a rotating shaft, a thread controlling element mounted on said shaft for rotation therewith and having means adapted to engage the thread for controlling the same, thread guides located at 110 opposite sides of said shaft and said thread controlling element and disposed so that the thread passing between said guides is led into engagement with the peripheral surface thereof, a shaft extending in a direction at 115 right angles to a plane containing the axis of the shaft supporting said thread controlling element on which said thread guides are mounted, said thread guides being disposed at one side of the axis of the shaft supporting the same whereby when said shaft is rotated said thread guides are moved away from the thread controlling element and rendered accessible for threading.

2. A thread controlling mechanism for 125 sewing machines including a rotating shaft, a thread controlling element mounted on said shaft for rotation therewith and having means adapted to engage the thread for controlling the same, thread guides located at 130

- opposite sides of said shaft and said thread controlling element and disposed so that the thread passing between said guides is led into engagement with the peripheral surface thereof, a shaft extending in a direction at right angles to a plane containing the axis of the shaft supporting said thread controlling element on which said thread guides are mounted, said thread guides being disposed at one side of the axis of the shaft supporting the same whereby when said shaft is rotated said thread guides are moved away from the thread controlling element and rendered accessible for threading, yielding means connected to said shaft for holding the thread guides in normal position for cooperation with the thread controlling element and means carried by said shaft for turning the same.
3. A thread controlling mechanism for sewing machines including a rotating shaft, a thread controlling element mounted on said shaft for rotation therewith and having means adapted to engage the thread for controlling the same, thread guides located at opposite sides of said shaft and said thread controlling element and disposed so that the thread passing between said guides is led into engagement with the peripheral surface thereof, a shaft extending in a direction at right angles to a plane containing the axis of the shaft supporting said thread controlling element on which said thread guides are mounted, arms attached to the shaft and extending at right angles thereto for carrying the respective thread guides, said arms being independently shiftable on said supporting shaft, yielding means for holding said shaft in a set position with said thread guides in normal thread guiding position and means attached to the shaft whereby it may be turned to move said thread guides to position the same for threading.

In testimony whereof, we affix our signatures.

CHARLES F. RUBEL.
FREDERICK F. ZEIER.
